UNITED STATES PATENT OFFICE.

WILLIAM JAMES DORGAN, OF GRANTWOOD, NEW JERSEY.

CURRENT-LOCK FOR AUTOMOBILES.

1,217,719.

Specification of Letters Patent. Patented Feb. 27, 1917.

Application filed November 10, 1915. Serial No. 60,685.

To all whom it may concern:

Be it known that I, WILLIAM J. DORGAN, a citizen of the United States, and a resident of Grantwood, in the county of Bergen and State of New Jersey, have invented a new and Improved Current-Lock for Automobiles, of which the following is a full, clear, and exact description.

This invention relates to safety appliances adapted especially for automobile practice, although without material alteration the construction may be used to advantage in many other fields of operation.

Among the objects of the invention is to provide a lock adapted to open or close a pipe or line along which the current is adapted to flow when the pipe or line is open, the means for controlling the condition of the pipe or line being of a permutation character, making it feasible for the owner or authorized person to open the lock with facility, but whereby it will be practically impossible for a stranger to open it.

Another object of the invention is to provide a locking means for an automobile providing for the cutting off of the flow of gasolene, or its equivalent, to the motor, and at the same time breaking the circuit between the magneto or other source of electrical energy and the spark plugs.

A further object of the invention is to provide a lock of the character set forth, requiring no key or other separate parts for manipulation thereof, and also of such a construction that the opening of the lock may be effected without requiring the use of a light, the action of the lock being controlled by the operator's sense of touch rather than by his sight.

With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference characters designate the same parts in the several views, and in which—

Figure 1 is a vertical longitudinal section of a portion of an automobile showing my improved lock applied thereto;

Fig. 2 is a bottom plan view of the lock as seen from the line 2—2 of Fig. 1 but with

the right hand portion of the lock in Fig. 1 turned over to the left in Fig. 2;

Fig. 3 is a plan view of the lock but with parts in section on the broken line 3—3 of Fig. 4;

Fig. 4 is a vertical section on the line 4—4 of Fig. 3;

Fig. 5 is a horizontal section on the line 5—5 of Fig. 4;

Fig. 6 is a vertical section corresponding to the sectional part of Fig. 4 but with the parts separated;

Fig. 7 is a plan view of the adjustable disk associated with the valve plug; and

Fig. 8 is a plan view of the valve plug.

As above premised, the lock is designed especially for automobile practice, and at any convenient place in the vehicle body as, for example, in the floor 10 thereof just in the rear of the dashboard 11 I mount in any suitable rigid position the valve body 12. The position of this body 12 with respect to the floor of the car may vary considerably with respect to different types or makes of cars, but the principle of operation would be the same in all of them.

The valve body is shown for convenience as of substantially rectangular form in plan view and adapted for the employment of four independent rotary valve plugs 13, one at each corner. I wish it to be understood, however, that the number of valve plugs and their relative arrangement may be varied as conditions dictate. The valve body is cored at 14 providing a passageway from a supply tube 15 to a delivery tube 16, said passageway being free and unobstructed when the valve plugs are all turned to open position as shown in Fig. 5. By way of illustration, the supply tube may be understood as being connected with any suitable source of fuel supply, either as gasolene or a mixture prepared by the carburetor for the engine cylinders, and the delivery pipe 16 will be understood as leading toward the engine. When the valves are open as herein shown, there will be no obstruction to the usual supply delivery of the fuel to the motor, the fluid flowing through the passageway 14. If, however, any one or more of the valves be turned,

the flow or current of the fluid will be stopped through the body 12 of the lock and hence the motor will be incapacitated.

The main portion of each valve plug may be made, as heretofore, as a conical device

fitted snugly in the correspondingly shaped seat 17 and provided with a transverse bore 14' communicating with the main portions of the passageway 14 when the valve plug is in open position. The valve plug is adapted to be secured in position in the seat 17 by means of a screw 18 or its equivalent acting through insulation washers 19 and 20 and into a hole in the end of the valve plug. A metal washer 21 is located between the washer 20 and the body 12.

Any suitable temporary catch means may be provided to hold the valve plugs in any position to which they may be adjusted, 15 but permitting them to be turned from such positions when required. For this purpose I provide for each valve a plunger 22 mounted for reciprocation in a socket 23 formed in a rib 24 constituting a part of the 20 valve body. A spring 25 located in the socket 23 acts upon the plunger serving to force it outwardly into engagement with any one of a series of notches 26 formed in the periphery of a disk 27 carried by or 25 constituting a part of the valve plug. A specific description of one of the valve plugs will be understood as being applicable to all of them, since they are or may be all of similar construction. Said disk periphery 30 is constructed in a peculiar manner, having the notches arranged in a group but providing an un-notched or smooth portion 26'. The operator, therefore, upon rotating the valve plug by means of a knob 28 or its equivalent will be able to determine by the 35 sense of touch when the smooth portion 26' of the periphery is passing along the plunger. Any authorized party knowing, for example, that the valve will be open 40 when the disk is located in a certain position with respect to the plunger, such position bearing a certain definite relation to the smooth portion of the periphery, he obviously may turn the knob or valve plug to 45 such predetermined position, depending merely upon his sense of touch. More definitely stated, assuming that any valve will be open when the second notch is reached when the valve plug is turned in a clockwise direction, the operator will turn the 50 valve freely in order to locate the smooth portion of the periphery, and then he can tell positively by the sense of touch when the plunger snaps into the second notch. 55 He may or may not know the location of the plunger with respect to the valve plug for this purpose. Likewise the remaining valve plugs may be so adjusted as to make them open when turned through any desired angle after the passage of the smooth portions along the respective plungers.

In order to provide for a variation in the combination or adjustment of the valves so as to have the passageway free and unobstructed, I provide the disks separate from

the valve plugs and each held from rotation on its valve by means of a pin 29 or its equivalent engaging in any one of a series of openings 30 shown in this instance as being arranged radially between the respective notches 26 and the axis of the valve. The pin 29 projects sufficiently far above the upper surface of the disk to be engaged by a lug 31 projecting radially at the lower end of the knob 28. I show two of these 75 lugs 31, but as to this special structure I do not wish to be limited. Suffice it to say that by providing a certain amount of clearance for free independent movement of the knob around the removable pin connection 80 32 therefor, added confusion results to the stranger attempting to tamper with the device. Assuming that Fig. 3 shows the valves all open and with the pins 29 located inwardly toward the center of the body 12, 85 the adjustment of the several disks will indicate that the combination of the four valves is as follows, beginning at the lower left hand corner and following the course of the fluid: second notch to the right, second notch to the right, second notch to the right, and fourth notch to the left, the knobs being shown in this construction as being 90 left standing in the positions to which they had been moved to open the lock. 95

To lock the car, therefore, the operator will turn any one or more of the valves from the position just described. Such turning may be in either direction and to any angular degree greater or less than 360 degrees. 100 On the return of the operator to the car preparatory to starting, he has but to return the disturbed valve to its normal open position as above described. If more than one valve have been closed, the restoration, of 105 course, will be necessary to open the lock.

The several locks may be inclosed within a movable cover plate 33 or the like to protect them from accidental disturbance, such cover plate being adapted to close automatically when allowed so to do, and the knobs 28 may have shanks long enough to reach to any desired distance below the floor of the car or said movable cover plate. 110

As shown best in Fig. 2, the same locking or safety device may be associated with the electric circuit between the magneto or other source of energy and the spark plugs, such line being shown at 34 and 35. At 36 is shown a switch rigidly connected to the valve plug as by means of the screw 18 and washers 19 and 20. The switch is shown in the form of a bell crank, the free ends of which are adapted to make electrical connection with a pair of spaced contacts 37. 115 Each of the contacts is connected either to the main line or to an auxiliary line 38 leading directly from one contact of one switch to a contact of the next switch, and so on throughout all of the series of valves and 120 125 130

switches. The switches are connected to the respective valve plugs in such position as to open the circuit or make electrical connection throughout the system when the passageway 14 is open for the fluid. This arrangement provides double security, cutting off both the fuel and the electricity at the same time when any one or more of the valve plugs are rotated out of normal running position. It follows also that the electrical locking means may be used either with or without the fuel passageway. The operation, however, of the permutation features of the lock and the adjustment thereof will be the same as already described. Each of the contacts 37 is adapted to be locked to the valve body by means of a screw 39, insulation washers 40 and 41 being provided.

I claim:

1. The herein described current lock for an automobile comprising, in combination, a rigid body of substantially rectangular form, a plug rotatably mounted in each corner of the body, a detent coöoperating with each plug and indicating to the operator through his sense of touch the relative position of the plug with respect to the

body, and means to convey a current through the body when the plugs are all in normal running position, said current being obstructed when any one or more of the plugs are turned out of such normal position.

2. In an automobile lock, the combination of a rigid body, a plurality of rotary members journaled therein, a disk fitted upon each rotary member, the rotary member and said disk being provided with interlocking parts providing for rotary adjustment of the disk around the axis of the rotary member, said disk having a series of peripheral notches on one side and being smooth on the other side, a series of plungers radiating outwardly from the center of the body into coöperation with the respective disks, means to rotate the several rotary members and disks, and means to convey a current through said body and through all of said rotary members when adjusted in normal running position.

WILLIAM JAMES DORGAN.
